PLASTIC BOX

Henry Dreyfuss, South Pasadena, Calif., assignor to Philip Morris Incorporated, New York, N.Y., a corporation of Virginia

Filed June 21, 1965, Ser. No. 465,398
1 Claim. (Cl. 206—16)

This invention relates to containers and refers more particularly to a molded plastic box adapted to hold a safety razor-blade dispenser combination.

An objective of the present invention is to provide a molded plastic box which embodies therein features of simplicity of construction, economy in manufacture, attractiveness in appearance, and durability in use.

Another objective is to provide a molded plastic box which is adapted to conveniently and securely hold a safety razor-blade dispenser combination for display purposes in a store, storage in a home and for traveling.

Another objective is to provide a molded plastic box having a sculpted, aesthetic appearance, and wherein the hinge means connecting the cover and receptacle elements is located unobtrusively within the marginal extremities of the box.

According to the invention, the box comprises a receptacle and a cover therefor with these elements being essentially U-shaped in cross-section and such that the cover element which is hinged at the rear of the receptacle, and which is inverted and oriented 90° with respect to the receptacle will nest therein when the cover is closed. The hinge means utilized comprises pintles integral with the cover element which engage in pintle receiving slots at the rear of the receptacle. These slots are so formed that when the cover is closed, no obtrusive hinge projection extends outwardly of the rear side of the receptacle.

The invention will appear more clearly from the following detailed description when taken in conjunction with the accompanying drawings showing by way of example a preferred embodiment of the inventive concept.

In the drawings:

FIGURE 1 is a perspective view of the box of the present invention with the cover element in a closed position.

FIGURE 2 is a perspective view of the box with the cover element shown in an open position.

FIGURE 3 is a front elevational view of the box with the cover closed.

FIGURE 4 is a sectional view of the box as taken along line 4—4 in FIGURE 1.

FIGURE 5 is a fragmentary vertical sectional view on enlarged scale as taken along 5—5 in FIGURE 3 and illustrates the latching means employed for maintaining the cover element in closed position.

FIGURE 6 is the same as FIGURE 5 except that the cover is slightly ajar of its fully closed position.

FIGURE 7 is a rear elevational view of the box illustrating the hinge means used for connecting the receptacle and cover elements, a portion of the receptacle floor being broken away to illustrate details of the hinge elements.

FIGURE 8 is a fragmentary top plan view illustrating in detail the hinge means employed for connecting the cover and receptacle elements, the cover being in an open position.

FIGURE 9 is a sectional view as taken along the line 9—9 in FIGURE 7.

FIGURE 10 is a sectional view as taken along the line 10—10 in FIGURE 1.

Throughout the description, like reference numerals are used to indicate like parts.

Referring now in detail to the drawings, the box 10

2

comprises a receptacle 12 and a cover 14 which is hingedly connected to the rear of the receptacle 12. The receptacle 12 as seen has an elongated floor 16 and upstanding end walls 18 and 20, with the end walls preferably being molded integrally with the floor 16 and each having inner surfaces 22 which slope upwardly and outwardly longitudinally of the floor. In a transverse direction, the end walls also taper inwardly from bottom to top as shown and aid in giving the box a sculpted, streamlined contour. As best seen in FIGURES 1 and 2, the front and rear surfaces of the receptacle extend longitudinally a short distance beyond the end walls to form skirts 24 which, in addition to being of a decorative character for enhancing the aesthetic qualities of the box, may serve as supporting members if it is desired to display the box upright on an end. To further add to the appearance of the box, the receptacle 12 and cover 14 are made in contrasting colors. In particular, the receptacle 12 is preferably made of a translucent or opaque plastic material, while on the other hand, the cover 14 is made of clear or transparent plastic material.

A particular embodiment of the box is adapted to serve as a container for a safety razor-blade dispenser set. To that purpose, end wall 18 of the receptacle has a transversely widened, vertically directed slotted recess 26 which supportingly receives the shaving head 28 of safety razor 30 of known type and shown in phantom detail in the drawings. As best seen in FIGURE 4, the bottom or heel of the recess 26 is formed with a horizontal shoulder 32 which terminates at a vertical opening 34 extending through the floor 16. The latter constitutes a drainage hole to permit moisture to exit from the box such as may be present on the safety razor from rinsing same after shaving. Similarly, the other end wall 20 of the receptacle has a smaller slotted recess 36 as seen in FIGURES 4 and 10 wherein is supported the end of the razor handle 38, the recess 36 being rounded at the bottom as at 40 to locate or position the handle.

The slotted recesses 26 and 36 are as seen in FIGURE 2, positioned somewhat towards the rear half of the receptacle 12 to provide space at the front part thereof for supporting a razor blade dispenser 42, the latter being of a known type for example, a double edge razor blade dispenser and like the razor 30, being shown in phantom detail in the drawings. The latter space is in the form of an elongated slotted opening forming a well 44 generally slightly larger in dimension than the razor blade dispenser package with the well 44 being stepped as at 46 to form therein a shoulder on which the razor blade dispenser is actually supported.

The underside of floor 16 of the receptacle is provided with a pair of transversely extending support feet 48, 50 as seen in FIGURE 4. In addition, the underside of the receptacle floor adjacent the longitudinal ends of well 44 is provided with downwardly directed hook elements 52, 54 which as best seen in FIGURE 7 may be engaged on the tabs 56 of a display card 58 or other support surface, the latter being shown in part section only.

Cover member 14 has an elongated flat top or crown portion 60 at the front and rear of which is connected front and rear downwardly directed sides 62 and 64 respectively as best seen in FIGURE 10. As seen in FIGURE 2, the front side 62 of the cover carries at the bottom integral latch hooks 66, 68 which when the cover is closed, engage in the latching recesses 70, 72 located in front of the well 44 in the receptacle floor 16 for holding the cover in a securely closed position. Front side 62 also is provided with an outwardly projecting boss 74 which defines a section 76 on the wall against which a user applies finger pressure to open the box. The purpose of the latter will be described in detail later on in the description.

An important feature of the box of the present invention is that the cover 14 is connected with the receptacle by hinge means which are located fully within the extremities of the rear of the receptacle so that the hinges do not detract from the overall streamlined appearance of the box. To that end, the rear side of the cover is provided at the bottom with integral lugs 78, which extend outwardly therefrom at an angle and which each carry a lateral pindle 80, the pindle extending symmetrically on either side of the lug. As seen in FIGURE 9, rear side 64 of the cover curves inwardly near the bottom as at 82 to strengthen the wall structure and to obviate interference between the lower edge thereof and the receptacle floor when rotated relative thereto.

The pintles 80 each fit into pindle receiving recesses 84 at the rear of the receptacle floor. As seen in FIGURE 7, the pindle recesses 84 are shaped as an inverted T and open inwardly with entry slots 86 from the rear margin of the receptacle, the latter providing a clearance space wherein the lugs 78 may ride when the cover is swung to an open position. As shown in FIGURE 9, the pindle recesses also open upwardly from the underside of the floor so that the recess has a horizontally widened lower portion 88 which acts as a bearing surface for the pindle. The widened lower portion 88 constitutes the cross bar of the inverted T while the central vertical slotted portion 90 constitutes the staff thereof. The forward or upper front side of each pindle recess is inclined inwardly of the receptacle floor as at 92 to receive the similarly inclined lugs 78 when the cover is closed.

The manner in which the cover 14 is connected to the receptacle 12 is illustrated in FIGURE 9. To make the connection of these elements, the pintles 80 are first positioned below the pindle recesses 84 in the receptacle floor with the pintles in register with the widened lower portion 88 of the recesses. The front lower surface 94 of lower portion 88 is inclined towards the rear of the receptacle so that at the point 96 where it intersects with inclined surface 92, the pindle recess is of slightly lesser dimension than the diameter of the pindle. As the pindle is pulled directly upwardly in the pindle recess, it will spread the surfaces defining the recess apart sufficiently to permit the pindle to ride above point 96 after which the surfaces will return to their normal position. Since the pindle diameter is greater than the pindle recess dimension between point 96 and the rear face 98 of the recess, the pindle will remain securely engaged therein.

FIGURES 5 and 6 illustrate the manner in which the latch hooks 66, 68 function for latching the cover 14 in closed position. As seen in the foregoing figures, the latch projections each have an inclined wedge-like front portion 100, so that when the cover is swung from an open to a closed position, the wedge portions 100 will strike against the chamfered upper edges 102 of inwardly directed flat ledges 104 in each latching recess 70, 72 and flex inwardly permitting the wedges to ride down on the edges 102. When the flat shoulder-like upper surface 106 of each wedge has located itself below the lower face 108 of the ledges 104, the front side 62 of the cover will spring forwardly locating the wedges 100 beneath the ledges 104 as seen in FIGURE 5. If it is thereafter desired to open the box, the user merely applies finger pressure against the front side section 76 to flex the side inwardly. The latter action frees the latch projections from under the ledges and the cover may then be raised to an open position.

As best seen in FIGURE 1, the front and rear sides 62 and 64 of the cover 14 curve downwardly and inwardly at the ends as at 110 to conform to the slope of the receptacle walls 18 and 20 to permit the cover to nest within the receptacle with the respective sides and walls in abutting relation.

As seen in FIGURE 10, the top 60 of the cover 14 carries a downwardly depending finger 112 at the underside thereof. The finger extends, with the cover in closed position, almost into contact with the razor blade dispenser 42. The finger 112 thus acts as a retainer to prevent the dispenser from becoming loose within its supporting well if the box is tilted on set up in display position on an end.

While there is above disclosed but one embodiment of the plastic box of the present invention, it is possible to produce still other embodiments without departing from the scope of the inventive concept herein disclosed, and accordingly, it should be understood that all matter contained in the above description or shown in the accompanying drawings shall be interpreted as illustrative and not in a limiting sense.

What is claimed is:

A molded plastic box adapted to hold a safety razor-blade dispenser combination comprising a receptacle having an elongated floor with parallel front and rear margins, and a pair of opposed end walls extending upwardly and longitudinally outwardly of the ends of said floor, said floor and end walls having substantially smooth surfaces devoid of protuberant structure, each of said end walls having a slotted recess for receiving a corresponding end of the safety razor, said floor having an elongated stepped-down slotted opening extending longitudinally therein for receiving the blade dispenser, a cover having a top and vertically directed front and rear sides, 20 the edges of said cover top and front and rear sides having a shape conforming to the shape of the receptacle floor and end walls and abutting thereagainst and inset from the receptacle marginal extremities adjacent thereto when the cover is closed; hinge means connecting said cover 25 to said receptacle including lugs extending downwardly outwardly angularly from the rear side of said cover, pintles carried by the lugs and extending laterally thereof, the floor of said receptacle having pindle receiving recesses extending therethrough adjacent said rear margin, 30 said pindle receiving recesses opening up from the underside of said floor and each communicating with an entry slot extending inwardly from the rear margin of the receptacle, said pindle receiving recesses having upper front surfaces opposite said entry slots and extending frontally 35 angularly of said rear margin to provide a surface upon which said lugs nest when the cover is closed, said lugs riding outwardly of the receptacle through said entry slots when the cover is swung to an open position, latching means carried by said cover and said receptacle for latching 40 said cover in a closed position comprising a pair of spaced latch projections carried by said front side and each having a frontally directed horizontal shoulder thereon, the floor of said receptacle having vertical slots receiving said latch projections, said vertical slots having horizontal ledges therein extending inwardly of the front margin of said receptacle, said shoulders locating beneath said ledges for holding said cover closed, the front side of said cover intermediate said latch projections having a projecting boss surface defining a section against which 45 45 finger pressure can be applied to deflect said front side inwardly for releasing said shoulders from beneath said ledges.
